FIG. 1 is a top, front, right side perspective view of a
charging case for wireless earphones, shown open in a first
configuration;

FIG. 2 is a top, front, left side perspective view of the
charging case for wireless earphones of FIG. 1, shown
closed in a second configuration;

FIG. 3 is a bottom, rear, right side perspective view thereof;

FIG. 4 is a front elevation view thereof;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines in the figures depict portions of the
charging case for wireless earphones that form no part of the
claimed design.

1 Claim, 9 Drawing Sheets
